Primary Examiner — Patricia A Palasik*(74) Attorney, Agent, or Firm* — Muncy, Geissler, Olds & Lowe, P.C.(57) **CLAIM**

We claim the ornamental design for a miniaturized semiconductor manufacturing device, as shown and described.

DESCRIPTION

FIG. 1 is a top, front, right perspective view of a miniaturized semiconductor manufacturing device showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings illustrate portions of the miniaturized semiconductor manufacturing device which form no part of the claimed design.
